DESIGN FOR A DRESS

Caroline Della Monica, New York, N. Y.

Application June 20, 1946, Serial No. 130,878

Term of patent 3½ years

(Cl. D3—26)

To all whom it may concern:

Be it known that I, Caroline Della Monica, a citizen of the United States of America, residing in New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

I claim:

The ornamental design for a dress, substantially as shown.

CAROLINE DELLA MONICA.
